UNITED STATES PATENT OFFICE.

FRANK B. WHIPPLE, OF ERIE, PENNSYLVANIA.

SLEEPING-CAR.

SPECIFICATION forming part of Letters Patent No. 234,899, dated November 30, 1880.

Application filed February 28, 1880.

To all whom it may concern:

Be it known that I, FRANK B. WHIPPLE, a citizen of the United States, residing at Erie, in the county of Erie and State of Pennsylvania, have invented certain new and useful Improvements in Railroad-Car Seats and Cars; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention consists in providing means whereby the car-seats of an ordinary car or day-coach may be adjusted so as to form beds, thus enabling an ordinary day-coach to serve as a sleeping-car.

20 A second part of my invention consists in providing devices to be attached to the side of the car, so that it can be divided into compartments.

25 My invention will fully appear in the following description and claims.

My invention is illustrated in the accompanying drawings, as follows: Figure 1 is an elevation of four car-seats, looking from the aisle, of which two are in position as seats for 30 day use and two are shown as converted into a bed, and one of the folding partitions is shown extended and in position to form one end of a compartment. Fig. 2 is a transverse section of one side of the car, and shows a side elevation of one of the folding partitions as extended. Fig. 3 is a plan view of the frame-work of the seats.

35 My convertible seats, when in use as seats, are hardly distinguishable from ordinary car-seats. They can be reversed, so as to face in either direction, and have all the characteristics of ordinary car-seats. When used for sleeping purposes the back and seat of one seat and the seat of the other seat form the horizontal part of the couch, while the back of the second seat is placed at an angle to serve as a pillow or raised head-part of the couch similar to lounges. If, however, it is not desired to have the head part raised, the device may be 45 so constructed as to have the four parts of the two seats lie horizontal; but as it is expected

that cars equipped with these seats will not be furnished with bed-clothing, &c., but will be designed and used for affording cheap sleeping accommodations, it will be desirable that 55 the head part of the couch be raised slightly to serve as a pillow.

I am aware that in most, if not all, forms of sleeping-cars the backs and seats of the car-seats form the bed by being brought to a horizontal position; that when so adjusted they are supported between the seat-frames by a ledge on the side of the car at one side, and by a rave or rail which is in the form of a slide, and draws out of the seat-body on the other 65 side or aisle side of the bed; but the seats of sleeping-cars are not reversible, they face each other in pairs, and between each pair is a permanent back of wood, which forms the head or foot board of the bed or berth, and the seat 70 and back cushions are loose and removable.

In the ordinary reversible day-coach seat the back is provided with a rigid T-iron of proper length, and by this they are pivoted to the arms of the seat and can be reversed by turning on this pivot; but the angle of the back when in position for use cannot be changed, nor can the back be brought to a horizontal position on the seat-line.

80 In order to enable the back of the seat to be reversible, as in an ordinary day-coach seat, and also to be so it can be laid flat or placed at an angle so as to form, in one case, a part of the horizontal part of the bed, and in the other case to form the inclined head part of 85 the bed, I substitute for the T-iron a link which is pivoted at one end to the seat-frame, as is the T-iron, and at the other end it is pivoted to the seat-back.

In the drawings, A represents the seat-frame; 90 B, the seat-back; C, the seat-bottom; D, the swinging bar, which forms a support for the seat-bottom when in place for forming a bed; E, the rave or rail along the side of the car, which forms a support for the opposite end of 95 the seat-bottoms. L is the link above referred to, which is pivoted at one end to the seat-frame, as at a, and at the other end to the seat-back, as at b.

F is a folding partition to divide the car into 100 sections. H is a bolt or catch for securing the seat-back in various positions.

When the seat-back is in position for forming a seat, as at the right of Fig. 1, its lower edge rests in notches formed in the seat-frame at the proper place, or it may be secured in 5 proper place by a bolt or catch or any other convenient device; and when the car-seat is in this position the seat-bottom is adjusted precisely the same as in any ordinary car-seat.

10 The bar D, when the car-seat is in use as a seat, is folded against the front rail, D', of the seat-frame, as seen in Fig. 2, and in Fig. 3 it is shown as nearly folded.

To make a proper-appearing finish the rail 15 D' is ledged so as to receive the bar D, as shown in Fig. 3. This swinging bar D, when in position for converting the seats into a bed, rests its free end in any proper form of catch on the side of the seat-frame in front of the one 20 to which it is hinged.

At the left of Fig. 1 the seats are shown as converted into a bed. It will then be seen that the two seat-bottoms are drawn together. One seat-back is lying flat, and the other 25 nearly so. The width of the two seat-bottoms and the back is such that all four cannot lie flat. Either seat-back may lie flat, but not both, while the seat-bottoms are both in between them. Of course, if the width of these 30 parts was changed properly they could all lie flat at once, as is the case in an ordinary sleeping-car; but, as before stated, the construction shown in the drawing is desirable in cars which are intended to afford cheap sleeping 35 accommodations, as by it the head is raised sufficiently to avoid the use of pillows.

If desired, the backs, when in the position for forming a bed, may be secured by a bolt or catch, as by the bolt H shown; but I do 40 not desire to be limited to any form of bolt or catch device for this or any other of the places or parts named, as this construction and application may be varied indefinitely.

The folding partition is in the form of an 45 ordinary folding fan, and is clearly shown in Fig. 2, and requires no further description. It folds into a recess in the side of the car, and when folded forms an ornamental panel. This partition may be used or not, as desired.

50 It will be observed that any two adjoining seats may be formed into a bed, while in sleeping-cars as at present constructed this is not the case. Of course, if the partitions F are used, it will be necessary to always make cer-

tain pairs of seats into beds in order to accommodate them to the partitions, unless the partitions are placed between all the seats, when such could be used as would properly screen the beds.

I am aware of the patents to A. Barbarin, 60 July 13, 1869, and H. S. Blood, November 23, 1869, and do not claim as new any of the features therein shown. In each of these patents a double-jointed link is used, but in neither case is it the same as mine, for I use no slots in my 65 links, and the pivots of the links are stationary. In each of the patents cited above the backs of the seats when used as a bed lie flat between the seats, while in my device the backs lie flat upon the seat-frames, and the 70 bottoms of the seats are placed between the seat-frames on the support formed by the swinging bar. The advantage of my construction is that the double-pivoted links, having no slots for changing the relative position of 75 the pivots, as in the other cases, are much simpler and more durable, and easier adjusted from one position to the other.

What I claim as new is—

1. In a railroad-car seat, the back connected 80 to the ends or frame by double-pivoted non-extensible links with pivot-holes, as described, whereby the said back may be reversed, as in an ordinary car-seat, or may be laid flat upon the seat-frame, or as nearly so as desired, so 85 as to form part of a bed, substantially as set forth.

2. In a railroad-car, the seats formed with 90 movable bottoms and backs, which are pivoted to the frame or ends of the seat by double-jointed non-extensible links or bars with pivot holes, as described, whereby any two adjoining seats can be formed into a bed by placing said backs in a horizontal, or nearly horizontal, position upon the seat-frame, and 95 adjusting the two movable bottoms beside them between the seats, substantially as set forth.

3. The folding partition F, constructed and arranged to operate substantially as and for 100 the purposes mentioned.

In testimony whereof I affix my signature in presence of two witnesses.

FRANK B. WHIPPLE.
